THE INTERNATIONAL SIGNAL CO., INCORPORATED, OF NEW YORK, N. Y.

TRAIN-STOPPING APPARATUS.

1,170,789.

Specification of Letters Patent.

Patented Feb. 8, 1916.

Application filed October 12, 1914. Serial No. 866,356.

To all whom it may concern:

Be it known that we, JEAN F. WEBB, Sr., and JEAN F. WEBB, Jr., residing at New York, in the county of New York and State of New York, have invented certain new and useful Improvements in Train-Stopping Apparatus, of which the following is a specification.

Heretofore several attempts have been made to produce an effective and reliable apparatus for controlling the operation of trains. Many of these attempts have been abortive, owing to the defects, of one character or the other, in the apparatus.

In order to be thoroughly effective, and reliable, a train stopping apparatus should have few parts; it should have provision for opening the air brake setting valve every time the train passes a predetermined place; it should have provisions for preventing the setting of the brakes when the train is to pass "safety"; it should have provision for effecting a setting of the brakes whenever an essential part of the apparatus is broken or damaged so as to become inoperative, and particularly when the train is passing a "danger" point.

It is therefore one of the objects of the present invention to provide an apparatus that will embody as fully as possible, the foregoing essential characteristics.

In the application filed Jan. 18, 1912, by Jean F. Webb, Jr., there is disclosed a train stopping apparatus which embodies an air valve, that is included in the air brake system, for releasing air to set the brakes. In such apparatus the valve is opened by a plunger actuated device every time the plunger passes over a tripping ramp located along the right-of-way, and if the train has to proceed without interruption (as when the run is clear) the valve is immediately closed by an auxiliary apparatus that includes a resetting arm, which is actuated by a track obstacle located along the right-of-way in close juxtaposition to the ramp, the obstacle being controlled by a block system, or otherwise, to project into the path of travel of the resetting arm, or not, accordingly as to whether or not the train is to be permitted to pass or is to stop. That apparatus, while embodying many advantageous features, requires two sets of devices on the train to coöperate with the valve, and two distinct track devices for operating the

two train carried devices, and is somewhat objectionable, both from the point of view of initial manufacturing and installation cost and from the view of up-keep expense.

The present invention therefore has for another of its objects to simplify the construction, reduce the number of mechanical parts, combine the valve opening and the valve closing mechanisms into a single structure whereby the movement of the plunger may be utilized to perform both the opening and closing acts in connection with the tripping ramp alone, thereby eliminating the second track fixture and the train carried resetting arm heretofore employed.

Again, it is an object of the present invention to provide a train stopping apparatus capable of initiating a danger indication and suppressing that indication when the line is clear, by mechanism which uses only a single ramp located along the right-of-way and a single plunger on the train to effect the co-operation between the train carried apparatus and the roadway apparatus, in lieu of a plunger and resetting arm on the train and a setting ramp and a suppressing controlled track fixture along the right-of-way.

Generically the present invention includes an air valve (or other danger indicating device) a plunger which always positively opens the valve on its upward movement and also acts (when co-operatively connected) to reclose the valve (a suppression of danger indication) on the downward movement of the plunger, electro-operative means being provided for effecting co-operative connection between the plunger and the valve when resetting or suppression is desired, and a single track obstacle or ramp for effecting the mechanical action of the plunger and closing the electric circuit that controls the action of the electro-operative means.

With other objects in view, which will appear to those skilled in the art, the invention also resides in those novel details of construction, combination and arrangement of parts, all of which will be first fully explained, then be specifically pointed out in the appended claims and illustrated in the accompanying drawings, in which:

Figure 1 is a vertical section taken on the line 1-1 of Fig. 3, a portion of the plunger support and the plunger structure being shown in vertical section. Fig. 2 is a horizontal section on the line 2-2 of Fig. 1. Fig.

3 is a vertical cross section on the line 3—3 of Fig. 1. Fig. 4 is a horizontal section on the line 4—4 of Fig. 1. Fig. 5 is a view similar to Fig. 1, showing the position of the parts 5 at the time the plunger is being elevated and has moved the valve holding shaft through the initial part of its movement, the electro-magnetic mechanism being shown as energized with the resetting pin projected. Fig. 10 6 is a side elevation of the rigid plunger head. Fig. 7 is an end view of the same. Fig. 8 is a diagrammatic view showing one manner of effecting the electrical connection to control the electro-operative devices.

15 In the drawings, in which like numerals indicate like parts in all the figures, 1 represents the housing which is adapted to be secured to the locomotive at any convenient or desirable location, preferably, however, 20 on the front buffer beam, and the casing 1 is, in practice, insulated from the metallic parts of the locomotive for a purpose that will later appear.

25 The casing 1 is provided with bearings 2 in which the valve holding shaft 3 is located. The shaft 3 projects into the valve mechanism 20 (which valve mechanism may be of any approved type such, for instance, as is shown in the application filed by Jean F. Webb, Jr., on April 27, 1914, Ser. No. 30 834,866,) and 4 designates the operating cam that is keyed to the shaft 3 and is provided with an opening projection 5 and a closing projection 6. In addition to the foregoing 35 projections, the cam 4 is provided with an arm 7 that has a holding notch 8 to receive the spring latch 11 that holds the shaft from accidental displacement, the arm 7 having a cam surface 10 whereby when the shaft 40 3 is turned to release the latch from the notch 8, the resiliency of the latch will continue the rotation of the shaft until the latch finger engages a second projection 9 to arrest the opening movement imparted by 45 the spring latch 11.

12 is a lug carried by the lever 7 to coöperate with the projections 17—18 on the head of the resetting rod 13, the resetting rod passing through a bearing 14 with which it 50 has a pin and slot connection 15. A spring 16 presses the resetting rod to the position shown in Fig. 1. The resetting rod 13 is a manual resetting rod that is adapted to be connected up in such manner that the engineer by pulling the rod 13 can reset the shaft 3. The head of the resetting rod 13 is also 55 guided in a dove-tail slot 19 in a portion of the casing (see Fig. 3).

60 As before stated, the valve 20 may be of any approved construction, and we have therefore simply diagrammatically illustrated the same in Fig. 3 of the drawings, as the construction of the valve, *per se*, forms no part of the present invention.

65 21 is the plunger guide in which the

plunger 22 is operative. The plunger 22 has a stem 23 which is flattened at 24 to pass through an aperture of similar cross section in the cap 61 to prevent swiveling of the plunger, and to the upper end of the plunger, 70 a rigid head 42 is secured as also will be later explained.

The plunger 22, in the preferred form of the invention, is made of sections whereby the contacting or shoe end may be replaced, 75 when broken or worn, in a convenient manner, and at a minimum expense.

The plunger 22 is bored at 25 to receive the bolts 26, a flat face of the head of each of which is adapted to engage the flat portions 24 of the plunger to prevent swiveling of the bolts, and the bolts are held down by a plate 28 that is engaged by the spring 29 that serves to lower the plunger and tends to hold it down. The lower or shoe section 85 of the plunger includes a plunger engaging part 30, a shoe proper 34 and a connecting neck 33, the plunger engaging part 30 being bored at 31 to permit passage of the bolts 26 and the portion 30 is secured in place by 90 nuts 32.

The joint between the main section of the plunger and the shoe section is made air tight by a ball and socket joint, or a gasket or any other desired method. 95

35 designates a blind air bore that extends down through the stem 22 into the shoe section of the plunger through the portion 30 and the neck 33 and may be extended down into the material of the shoe 100 proper 34.

37 is an air lead pipe that is secured to plunger 22 by fixture 36 at the top of bore 35, and connected by union lug 38 to pipe 39 that leads to the train pipe of the air brake 105 system. In this manner, the train pipe air pressure may be maintained in the blind bore 35 so that in the event of a breakage of the neck 33, or the stem 22, the air brakes will be set. 110

The head 42 may be of the split or divided type and includes the base parts 40, which are provided with ears 41 through which clamping bolts or screws are fastened to secure the head rigidly to the upper end of 115 the plunger. The head 42 has a pin bearing 43 which is adapted to be suitably bushed to receive the resetting pin 46. The head 42 is also provided with ears 44 to which the yieldable head 45 is pivoted. While it is 120 preferred to have the head 45 yieldable yet it is not an absolute essential to have the same yieldable.

By making the head 45 yieldable one way (i. e., by mounting it pivotally) should the 125 train be stopped while the plunger is on the ramp with the head 45 up above the cam 5 (a position it sometimes assumes when the valve is all the way open) an attempt to reset the valve manually will not tend to 130

break off the head, as it will yield sufficiently to permit the cam 5 to assume its normal position. As soon as the plunger leaves the ramp, the head 45 will disengage the periphery of the cam 5 and come back into alignment. Were the head not made yieldable, and the plunger stopped with the upper end of the head 45 having passed the nose of the cam 5 (the valve being wide open) it would be a very difficult matter, if not impossible, to reset the valve until the train is moved on sufficiently to allow the plunger to drop off the ramp.

47 is a lever which is fulcrumed at 48 and has a pin and slot connection 49 with the resetting pin 46.

50 is an extension bracket from the head 42 which bracket is provided with a saddle 51 in which the electro-magnet 52 is secured. The armature 53 of the magnet 52 (the magnet being of the solenoid type) has a pin and slot connection 54 with the lever 47 and is designed to rock the lever on its pivot to project the pin 46 when the magnet is energized. The lever 47 includes an extension 55 that has a latching notch 56 to be engaged by the shoulder 59 of the latch 57, the latch being pivoted at 58 to the head 42 and having a finger 60 which, when the head 42 is resting on the cap 61, is engaged by the cap to move the latch to clear the latch notch 56, as shown in Fig. 1 of the drawings.

One terminal, 62, of the electro-magnet 52, is connected at 63 to the head 42 so as to effect an electrical connection with the plunger while the other terminal 64 is connected to a binding post 65 which is insulated from the bracket 50 and saddle 51. The binding post 65 is also connected to a binding post 68 on the frame by a coil spring 67 which acts as an electrical conductor. A wire 70 connects the binding post 68 with some part of the train, as for instance, the axle of the locomotive truck, the wire 70 passing through an insulated bushing 69 in the casting 1.

In Fig. 8, there is diagrammatically illustrated the train carried partial circuit which includes a plunger 22, the connection 62, the winding of the magnet 52, the connection 70 and the wheels 76 of the train, while the roadway partial circuit includes the rails 73, the source of energy 72, the controlling mechanism 74 (a key or a block system connection, or any other suitable controlling device) the connection 75 and the ramp 71.

From the foregoing, it will be observed that when the parts are in the normal position, they will lie as shown in Fig. 1 of the drawings, but when the train is in motion, and the shoe 34 engages a ramp 71, the plunger 22 will be raised, thereby causing the head 45 to engage the projection 5 of the cam 4 to turn the shaft in a clockwise direc-

tion in Fig. 1. This turning act releases the latch 11 from the notch 8 and throws the shaft over until the latch engages the notch 9, or until the head 45 has been elevated sufficiently to cause the latch to pass 70 the notch 9, and thereby open the air valve. Should the elevation of the plunger be incomplete, see Fig. 5 or should the elevation be partial only, for any reason, the shaft 3 will only be thrown over until the 75 notch 9 engages the latch, thus preventing the resetting projection 6 from coming into the path of the pin 46 before that pin can be projected. In other words, after the plunger is raised only to the extent indicated 80 in Fig. 5 (by engagement with some unauthorized track obstruction, for example) when the right of way is "clear", the pin 46 could not be projected if the shaft 3 made a complete or normal turn to the full open 85 position, because the pin would engage the peripheral face of the cam 6 which would lie in the way, hence, the notch 9 is provided to cooperate with the spring 11 and hold the shaft 3 from making a sufficient turn 90 to interfere with the projection of the pin 46, it being understood, of course, that the air brake valve is not open when the parts are in the position shown in Fig. 3, the opening act commencing immediately after 95 that position, while the shaft 3 moves until the member 12 engages the member 17.

Should the key 74 be closed when the shoe 34 engages the ramp, the electric circuit will be established and the magnet 52 energized 100 thereby rocking the lever 47 from the position shown in Fig. 1 to the position shown in Fig. 5, which causes the pin 46 to be projected over the resetting projection 6 so that when the shoe 34 leaves the ramp 71 and 105 drops through the action of gravity and the spring 29, the pin 46 will engage the resetting projection 6 and rotate the shaft 3 in a counter-clockwise direction in Fig. 1, to promptly reset the valve and suppress 110 the action of the same.

As soon as the plunger becomes elevated slightly so that the head 42 will clear the cap 61, the latch 57 will drop by gravity onto the toe of the lever projection 55 so 115 that the instant the magnet 52 is energized and the lever is rocked to the position shown in Fig. 5, the latch 57 will engage notch 56 and latch the lever in place so that should the electric circuit be immediately broken 120 the pin 46 will be held projected until it has performed its function. Thus, it will be seen that the period of energization may be but instantaneous and we do not depend upon the holding effect of the electric current to keep the pin 46 projected after it has been once set. The advantages of this construction are obvious.

If the circuit at the key 74 is open when the shoe engages the ramp, no effect will 130

be produced in the magnet 54 and hence the pin 46 will not be projected so that on the return movement of the plunger no effect on the projection 6 will take place, thereby leaving the air valve open and setting the brakes.

The brakes having been set, as above described, and the train brought to a standstill or to a predetermined speed, the engineer can reset the valve by pulling the rod 13.

From the foregoing description, taken in connection with the accompanying drawings, it is thought the complete construction, operation and advantages of the invention will be clear to those skilled in the art.

In conclusion, attention is called to the fact that this construction provides a train stopping apparatus of the double-action type which uses only a single plunger and a single ramp; it provides a train stopping apparatus capable of giving both an opening and a reclosing action on the valve of an air brake system by means of a single plunger device and a single ramp; it provides a train stopping apparatus whose plunger always positively opens the air valve on the upward movement and recloses the air valve on the downward movement when the reclosing act is desired; it provides a train stopping apparatus capable of giving a double-action when desired without the use of any special or auxiliary closing devices; it provides a train stopping apparatus without any roadside, intermittent or controlled tripping devices, yet capable of opening and instantly reclosing the air valve that controls the air brake system, by means of a single ramp; it provides a train stopping apparatus whose moving parts are made and so connected with the air brake system that they form a closed air duct, the construction being such that the breaking of any such moving part will allow the escape of air from the train line and set the brakes.

What we claim is:

1. In train stopping apparatus, an air brake valve, a member for holding the same closed, a plunger for moving said holding member to release said valve; a ramp for moving said plunger to effect the opening of said valve to initiate the action of the brakes; and mechanism coöperating with the plunger to effect an immediate restoration of said holding member to reclose said valve and thereby suppress the action of the brakes.

2. In train stopping apparatus, an air brake valve, a member for holding the same closed, a plunger for moving said holding member to release said valve; a ramp for moving said plunger to effect the releasing act and thereby initiate the action of the brakes, an electro operative mechanism co-operating with the plunger to effect an im-

mediate restoration of said holding member to reclose said valve and thereby suppress the action of the brakes.

3. In combination with means on a vehicle for initiating a danger indication, said means including an operating member; of means on the vehicle coöperating with said operating member when the same is moved in a direction opposite to the initiating movement for counteracting said indication; and means for effecting the coöperative connection between said counteracting means and said operating member; and mechanism located along the roadway for operating said operating member and controlling the action of said coöperatively connecting means, said roadway mechanism including a ramp for engaging said operating member.

4. The combination with a device on a vehicle that is adapted to be operated upon for a predetermined purpose; mechanism on the vehicle for initiating the operation of said device, mechanism on the vehicle for counter-acting said initiation, said mechanisms including a common plunger; and means along the roadway for effecting the operation of the vehicle mechanisms, said roadway means including a single obstacle to engage the plunger and effect the operative connection between said vehicle mechanisms and said roadway means.

5. The combination with a device on a vehicle that is adapted to be operated upon for a predetermined purpose; mechanism on the vehicle for initiating the operation of said device, mechanism on the vehicle for counter-acting said initiation, said mechanisms including a common plunger normally disconnected from said first mentioned device; means along the roadway for effecting the operation of the vehicle mechanisms, said roadway means including a single obstacle to engage the plunger and effect the operative connection between said vehicle mechanisms and said roadway means.

6. The combination of an air valve on a vehicle, mechanism on the vehicle for opening said valve, mechanism on the vehicle for closing said valve, said mechanisms including a common plunger; and means along the roadway for effecting the operation of the vehicle mechanism, said roadway means including a single obstacle to engage the plunger and effect the operative connection between said vehicle mechanisms and said roadway means.

7. In a system of the class described, a train carried apparatus including an air valve, means holding said valve closed, a device for releasing said holding means to permit said valve to open, said releasing device including a rotatable shaft, and a plunger adapted to engage said member when said plunger is raised to rotate said shaft; a tripping ramp engaging said

- plunger to raise the same; electro-mechanical means coöperative with said plunger to connect said plunger with said shaft to rotate said shaft in a counter-direction as said plunger falls and thereby reclose said valve. 5
8. In a system of the class described, a train carried apparatus including an air valve, means holding said valve closed, a device for releasing said holding means to permit said valve to open, said releasing device including a rotatable shaft, and a plunger adapted to engage said member when said plunger is raised to rotate said shaft; a tripping ramp engaging said plunger to raise the same; electro-mechanical means coöperative with said plunger to connect said plunger with said shaft to rotate said shaft in a counter-direction as said plunger falls and thereby reclose said valve, said electro- 15
- operative means including a train carried partial circuit which includes the wheels of the train and said plunger, and a track partial circuit which includes the rails and said ramp. 20
9. The combination with an air valve on a vehicle; a free plunger; a valve operating shaft including a member projecting from the shaft and adapted to project into the path of travel of said plunger when raised, to open said valve; a roadway ramp to actuate said plunger; and means coöperating with said plunger during its downward movement to reset said valve. 25
10. In an apparatus of the character stated, a stopping valve; an operating shaft; projections on said shaft; an operating plunger including a yieldable head to coöperate with one of said projections to turn said shaft, to release said valve; and means controlled externally to the aforesaid structure coöperative with said plunger and engaging another of said projections to restore said shaft and reclose said valve. 30
11. In an apparatus of the character stated, a stopping valve; an operating shaft; projections on said shaft; an operating plunger including a head to coöperate with one of said projections to turn said shaft to release said valve, and means controlled externally to the aforesaid structure coöperative with said plunger and engaging another of said projections to restore said shaft and reclose said valve. 35
12. In an apparatus of the character stated, a valve; a plunger normally operatively unconnected with said valve; means operatively connecting said plunger with said valve to open said valve as said plunger is moved in one direction; and means including a controlling device separate from the apparatus for operatively connecting said plunger with said valve to restore said valve to the closed position as said plunger is moved in the opposite direction. 40
13. In an apparatus of the character stated, a valve; a plunger normally operatively unconnected with said valve; means operatively connecting said plunger with said valve to open said valve as said plunger is moved in one direction; and electro-magnetically actuated means for operatively connecting said plunger with said valve to restore said valve to the closed position as said plunger is moved in the opposite direction. 45
14. The combination with an air valve on a vehicle; a free plunger; a valve operating shaft including a member adapted to be projected into the normal path of travel of said plunger when said plunger is raised to open said valve; a roadway ramp to raise said plunger; and means coöperative with said plunger, on its return movement, for resetting said valve. 50
15. The combination with an air valve on a vehicle; a plunger; a valve operating shaft including a member adapted to be projected into the normal path of travel of said plunger when said plunger is raised to open said valve; a roadway ramp to raise said plunger; and mechanically operated electrically controlled means coöperating with said plunger for resetting said valve. 55
16. The combination with an air valve on a vehicle; a plunger; a valve operating shaft including a member adapted to be projected into the normal path of travel of said plunger when said plunger is raised to open said valve; a roadway ramp to raise said plunger; mechanically operated electrically controlled means coöperating with said plunger for resetting said valve, said last named means including a vehicle-carried partial circuit that includes said plunger, and a complementary roadway partial circuit that includes said ramp. 60
17. In a mechanism of the class described, a valve operating body; a plunger normally disconnected from said body and including a head; a support in which said plunger is reciprocably held, said plunger adapted, when moved in one direction, to engage said body to move it one way; mechanism controlled at will from an external source, including a member to operatively engage said body, for moving it reversely as said plunger is moved in the opposite direction. 65
18. In a mechanism of the class described, a valve operating body; a plunger normally disconnected from said body and including a head; a support in which said plunger is reciprocably held, said plunger adapted, when moved in one direction, to engage said body to move it one way; electro-magnetic controlled mechanism, including a member to operatively engage said body, for moving it reversely as said plunger is moved in the opposite direction. 70
19. In a mechanism of the class described, a valve operating body; a plunger normally 75

- disconnected from said body and including a head; a support in which said plunger is reciprocably held, said plunger adapted, when moved in one direction, to engage said body to move it one way; electro-magnetic controlled mechanism, including a member carried by said head to operatively engage said body for moving it reversely as said plunger is moved in the opposite direction.
10. 20. In an apparatus of the class described, an air valve; means holding the same closed; a plunger normally disengaged from said holding means and mounted so as to be moved into engagement with said holding means to release the same; a normally retracted element adapted, when projected, to connect said plunger and holding means for the restoration of said holding means upon the reversed movement of said plunger; and means for projecting said element.
15. 21. In an apparatus of the class described, an air valve; means holding the same closed; a plunger normally disengaged from said holding means and mounted so as to be moved into engagement with said holding means to release the same; a normally retracted element adapted, when projected, to connect said plunger and holding means for the restoration of said holding means upon the reversed movement of said plunger; and electro-operative mechanism for projecting said element.
20. 22. In an apparatus of the class described, an air valve; means holding the same closed; a plunger normally disengaged from said holding means and mounted so as to be moved into engagement with said holding means to release the same; a normally retracted element adapted, when projected, to connect said plunger and holding means for the restoration of said holding means upon the reversed movement of said plunger; means for projecting said element; and a latch for latching said element, when projected, during the time said plunger is out of its inactive position.
25. 23. In an apparatus of the class described, an air valve; means holding the same closed; a plunger normally disengaged from said holding means and mounted so as to be moved into engagement with said holding means to release the same; a normally retracted element adapted, when projected, to connect said plunger and holding means for the restoration of said holding means upon the reversed movement of said plunger; electro-operative mechanism for projecting said element; and a latch for latching said element when projected during the time said plunger is out of its inactive position.
30. 24. A valve controlling shaft; a reciprocating plunger; a projection on said shaft to be engaged by said plunger when said plunger is moved in one direction; a second projection on said shaft; a pin on said plunger shaft adapted when projected, to engage said second projection to restore said shaft as said plunger is moved in the opposite direction, and means for projecting said pin.
35. 25. A valve controlling shaft; a reciprocating plunger; a projection on said shaft to be engaged by said plunger when said plunger is moved in one direction; a second projection on said shaft; a pin on said plunger adapted when projected, to engage said second projection to restore said shaft as said plunger is moved in the opposite direction, said plunger including a yielding head member to engage one of said projections, and a rigid head member in which said pin is mounted.
40. 26. A valve controlling shaft; a reciprocating plunger; a projection on said shaft to be engaged by said plunger when said plunger is moved in one direction; a second projection on said shaft; a pin on said plunger adapted when projected, to engage said second projection to restore said shaft as said plunger is moved in the opposite direction.
45. 27. A valve controlling shaft; a reciprocating plunger; a projection on said shaft to be engaged by said plunger when said plunger is moved in one direction; a second projection on said shaft; a pin on said plunger adapted when projected, to engage said second projection to restore said shaft as said plunger is moved in the opposite direction; means for projecting said pin; and means for securing said pin in its projected position.
50. 28. A valve controlling shaft; a reciprocating plunger; a projection on said shaft to be engaged by said plunger when said plunger is moved in one direction; a second projection on said shaft; a pin on said plunger adapted when projected, to engage said second projection to restore said shaft as said plunger is moved in the opposite direction; said plunger including a yielding head member to engage one of said projections, and a rigid head member in which said pin is mounted, and means for securing said pin in its projected position.
55. 29. A valve controlling shaft; a reciprocating plunger; a projection on said shaft to be engaged by said plunger when said plunger is moved in one direction; a second projection on said shaft; a pin on said plunger adapted when projected, to engage said second projection to restore said shaft as said plunger is moved in the opposite direction; means for projecting said pin; and electro-operative mechanism for actuating said pin projecting means.
60. 30. A valve controlling shaft; a reciprocating plunger; a projection on said shaft to be engaged by said plunger when said plunger is moved in one direction; a second

plunger is moved in one direction; a second projection on said shaft; a pin on said plunger adapted when projected, to engage said second projection to restore said shaft as 5 said plunger is moved in the opposite direction; said plunger including a yielding head member to engage one of said projections, a rigid head member in which said pin is mounted; and electro-operative mechanism 10 for actuating said pin projecting means.

31. A valve controlling shaft; a reciprocating plunger; a projection on said shaft to be engaged by said plunger when said plunger is moved in one direction; a second 15 projection on said shaft; a pin on said plunger adapted when projected to engage said second projection to restore said shaft as said plunger is moved in the opposite direction; means for projecting said pin; 20 electro-operative mechanism for actuating said pin projecting means; means for securing said pin, when projected, during the time the plunger is out of its normal position.

32. A valve controlling shaft; a reciprocating plunger, a projection on said shaft to be engaged by said plunger when said plunger is moved in one direction; a second projection on said shaft; a pin on said 30 plunger adapted when projected, to engage said second projection to restore said shaft as said plunger is moved in the opposite direction; said plunger including a yielding head member to engage one of said projections, a rigid head member in which said pin is mounted; electroc-operative mechanism 35 for actuating said pin projecting means; and means for securing said pin; when projected, during the time the plunger is out 40 of its normal position.

33. A valve holding shaft; an opening projection on said shaft; a holding ramp on said shaft; a latch coöperating with said

ramp; a resetting projection on said shaft; a reciprocating plunger normally disengaged 45 from said shaft and adapted when moved in one direction to engage said opening projection; said plunger including a bearing; a resetting pin held normally retracted in said bearing; a lever on said plunger, connected with said pin and adapted to project said pin; and means for operating said lever.

34. A valve holding shaft; an opening projection on said shaft; a holding ramp 55 on said shaft; a latch coöperating with said ramp; a resetting projection on said shaft; a reciprocating plunger normally disengaged from said projection and adapted, when moved in one direction, to engage said 60 opening projection, said plunger including a bearing; a resetting pin held normally retracted in said bearing; a lever on said plunger, connected with said pin and adapted to project said pin; and electro- 65 magnetic means for operating said lever.

35. A valve holding shaft; an opening projection on said shaft; a holding ramp on said shaft; a latch coöperating with said ramp; a resetting projection on said shaft; 70 a reciprocating plunger normally disengaged from said shaft and adapted when moved in one direction, to engage said opening projection; said plunger including a bearing; a resetting pin held normally re- 75 tracted in said bearing; a lever on said plunger, connected with said pin and adapted to project said pin, means for operating said lever; and a latch for holding said lever in its pin projecting position, and 80 means for releasing said latch.
